[57] CLAIM

The ornamental design for an amusement game, as shown and described.

DESCRIPTION

FIG. 1 is a perspective view of an amusement game showing my new design;

FIG. 2 is a front elevational view thereof; the rear elevational view being a mirror image thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an enlarged scale fragmentary elevational view of the scoring board taken along line 7—7 of FIG. 2; shown for clarity of illustration.

FIG. 1**FIG. 2****FIG. 3**

FIG. 4

FIG. 5

FIG. 6

FIG. 7
